SHOE SOLE

David Meyer, Kenmore, N.Y., assignor to W. J. Voit
Rubber Corp., a corporation of California

Filed Dec. 2, 1964, Ser. No. 82,882

Term of patent 14 years

(Cl. D7—5)

I claim:

The ornamental design for a shoe sole, substantially as shown.
